(57) **CLAIM**

The ornamental design for a rifle sponge, as shown and described.

DESCRIPTION

FIG. 1 is a top, front perspective view for a rifle sponge, showing my design;

FIG. 2 is a front elevation view thereof, with a rear elevation view being a mirror image of the front elevation view;

FIG. 3 is a right elevation view thereof;

FIG. 4 is a left elevation view thereof;

FIG. 5 is a top plan view thereof; and,

FIG. 6 is a bottom plan view thereof.
